UNITED STATES PATENT OFFICE.

HARRY T. LOCKWOOD, OF PHILADELPHIA, PENNSYLVANIA.

RAILWAY-RAIL JOINT.

SPECIFICATION forming part of Letters Patent No. 731,582, dated June 23, 1903.

Application filed September 9, 1902. Serial No. 122,703. (No model.)

To all whom it may concern:

Be it known that I, HARRY T. LOCKWOOD, a citizen of the United States, residing at Philadelphia, in the county of Philadelphia and State of Pennsylvania, have invented new and useful Improvements in Railway-Rail Joints, of which the following is a specification.

My invention relates to improvements in railway-rail joints; and it has for its general object to provide a simple and inexpensive joint through the medium of which the meeting ends of rails may be expeditiously and easily connected in a safe and strong manner without the employment of bolts and nuts and one which is so constructed that there is no liability of casual disconnection of the rails and yet the rails may be quickly and easily disconnected when desired.

With the foregoing in mind the invention will be fully understood from the following description and claims when taken in conjunction with the accompanying drawings, in which—

Figure 1 is a side elevation of the joint constituting the preferred embodiment of my invention with portions of one of the rails broken away. Fig. 2 is a perspective view of one of the rail-connecting plates forming part of the joint. Figs. 3 and 4 are enlarged transverse sections taken in the planes indicated by the broken lines 3 3 and 4 4, respectively, of Fig. 1. Fig. 5 is a perspective view of a portion of one rail, and Fig. 6 is an enlarged transverse section taken in the plane indicated by the broken line 6 6 of Fig. 2.

Similar letters of reference designate corresponding parts in all of the views of the drawings, referring to which—

A A are the rails of my improved joint, which are arranged end to end, as shown, and B B are the rail-connecting plates, which are disposed at opposite sides of the meeting portions of the rails and between the bases and heads thereof.

The rails A are similar in construction, and therefore a detailed description of the one shown at the right of Fig. 1 and in Fig. 5 will suffice to impart an understanding of both. Said rail is provided in the under side of its head a at its end and at opposite sides of its web b with recesses or sockets c, and it is also

provided in its base d at opposite sides of web b with recesses or sockets e and in the under side of its head a at opposite sides of web b with recesses or sockets f. The recesses or sockets f are preferably disposed above the recesses or sockets e and at about the proportional distance illustrated from the end of the rail. The rail-connecting plates B are also similar in construction and will both be understood by reference to the one shown in Figs. 2 and 6. The said plate in the preferred embodiment of the invention is made of one piece of steel or other suitable material and comprises upper and lower resilient arms g h, which are formed by bifurcating the ends of the plate and have rounded corners j, adapted to conform to the curvature of the rails, lugs k, arranged on the upper arms g in positions to enter the recesses or sockets f of the rails, lugs l, arranged on the lower arms h in positions to enter the recesses or sockets e in the rails, and a body portion m, arranged intermediate of the pairs of resilient arms and having a lug n, adapted to enter the alined recesses or sockets c of the rails and also having a base-flange p, arranged to bear on the bases of the rails and provided with notches q for the passage of the spikes used to fasten the rails to a sleeper or tie. 80

In the practice of my invention when the two alined rails A are to be joined the arms g h of the plates B are pressed and held together by any suitable means, and the plates are placed at opposite sides of the meeting portions of the rails, so that their lugs n enter the recesses or sockets c in the rails. The arms g h are then released, when they will spring in opposite directions, and thereby seat and hold their lugs k l in the recesses or sockets f e, respectively, of the rails. When the plates are arranged in the manner described relative to the rails, it will be observed that they will connect the rails in a strong and safe manner and will not be liable to be 90 casually displaced or disconnected from the rails by the shocks and jars to which rail-joints are ordinarily subjected, which is an important desideratum. When, however, it is desired to disconnect the plates from the rails, the same may be readily accomplished by prying or otherwise disengaging the lugs

on the arms *g h* out of engagement with the recesses or sockets *f e* and withdrawing the lugs *n* from the recesses or sockets *c*.

The recesses or sockets in the rails are preferably made slightly longer than the complementary lugs on the connecting-plates, as shown, in order not to interfere with the expansion and contraction of the rails.

I have entered into a detailed description 10 of the construction and relative arrangement of the parts embraced in the present and preferred embodiment of my invention in order to impart a full, clear, and exact understanding of the same. I do not desire, however, 15 to be understood as confining myself to such specific construction and relative arrangement of parts, as such changes or modifications may be made in practice as fairly fall within the scope of my invention as claimed.

20 Having described my invention, what I claim, and desire to secure by Letters Patent, is—

1. In a rail-joint, the combination of rails arranged end to end, and a connecting-plate 25 arranged at one side of the webs of the rails and between the bases and heads thereof, and having resilient arms at its ends; said rails and the arms of the plate being provided with coacting engaging means, held in direct 30 engagement with each other by the resiliency of the arms.

2. In a rail-joint, the combination of rails arranged end to end, and a connecting-plate arranged at one side of the webs of the rails, 35 and between the bases and heads thereof, and having bifurcations in its ends, and also having upper and lower resilient arms, formed by said bifurcations, and held by their resiliency in direct engagement with the bases 40 and heads of the rails.

3. In a rail-joint, the combination of rails arranged end to end, and having recesses or 45 sockets in their bases and heads, and a resilient connecting-plate arranged at one side of the webs of the rails, and having lugs adapted, in virtue of the resiliency of the plate, to be sprung into and out of the recesses or sockets in the bases and heads of the rails.

4. In a rail-joint, the combination of rails 50 arranged end to end, and having recesses or sockets in their heads at said ends, and also having recesses or sockets in their bases and heads at a distance from the ends, and a resilient connecting-plate arranged at one side

of the webs of the rails, and having a lug seated in the first-mentioned recesses or sockets of the rails, and also having lugs adapted, in virtue of the resiliency of the plate, to be sprung into and out of the second-mentioned recesses or sockets of the rails. 60

5. In a rail-joint, the combination of rails arranged end to end, and having recesses or sockets in their heads at said ends, and also having recesses or sockets in their bases and heads at a distance from the ends, and the 65 connecting-plate arranged at one side of the webs of the rails, and having a lug seated in the first-mentioned recesses or sockets of the rails, and also having bifurcations in its ends, and lugs on the arms formed by said bifurcations, adapted to be sprung into and out of the second-mentioned recesses or sockets of the rails. 70

6. In a rail-joint, the combination of rails, arranged end to end, and having recesses or 75 sockets in their bases and heads, and a metallic connecting-plate arranged between the bases and heads of the rails, and having bifurcations in its ends, and also having lugs on the arms formed by said bifurcations, re- 80 movably arranged in the recesses or sockets in the bases and heads of the rails.

7. In a rail-joint, the combination of rails arranged end to end, and having recesses or sockets in their bases and heads at opposite 85 sides of their webs, and connecting-plates arranged at opposite sides of the webs of the rails, and having resilient arms at their ends, bearing lugs arranged in the recesses or sockets of the rails. 90

8. In a rail-joint, the combination of rails arranged end to end, and having recesses or sockets *c f* in their heads at opposite sides of their webs, and also having recesses or sockets *e* in their bases at opposite sides of their webs, and connecting-plates arranged at opposite sides of the webs of the rails, and having lugs disposed in the sockets *c* of the rails, and base-flanges, and also having resilient arms at their ends bearing lugs arranged in the recesses *e f* of the rails. 100

In testimony whereof I have hereunto set my hand in presence of two subscribing witnesses.

HARRY T. LOCKWOOD.
